FUSIBLE MATERIAL

Frederic E. Sutter, West Caldwell, N. J., assignor
to Westinghouse Electric & Manufacturing
Company, East Pittsburgh, Pa., a corporation
of Pennsylvania

Application April 14, 1938, Serial No. 202,111

4 Claims. (Cl. 200—135)

My present invention relates to incandescent electric lamps and particularly to a fusible section which may be utilized in connection therewith to extinguish the lamp upon the occurrence 5 of abnormal current flow, and constitutes a continuation in part of my copending application Serial No. 125,545, filed February 13, 1937, and assigned to the same assignee as the present application.

It has long been the practice in the manufacture of incandescent electric lamps to employ a fuse in the base for the lamp or preferably to form a fusible section as part of the leading-in conductor which supplies the electrical energy for the filament. Although considerable progress has been made in the manufacture of incandescent electric lamps, especially in the quality of the tungsten filament and the leading-in conductors, there are, nevertheless, occasions when the filament becomes disrupted. This frequently causes the formation of an arc which travels along the filament supporting and leading-in conductors. When this arc continues for an appreciable period of time occasionally explosion of the lamp 25 occurs with possible resulting damage.

In order to obviate such contingency it has been the practice to form a section of the leading-in conductor of a special fusible material having definite current carrying characteristics so that upon the occurrence of abnormal current flow disruption of the fusible section follows thus interrupting current flow and preventing the undesirable formation of an arc with possible detrimental results. However, several problems exist 30 in connection with the selection of the proper fusible material as it must not only have the requisite current carrying characteristics but inasmuch as it is disposed in close proximity to the seal where the leading-in conductor passes through the glass envelope, it is preferable that it have a coefficient of expansion approaching that of the glass envelope.

Moreover, since the fusible section must be of a material differing from that of the metal forming the leading-in conductor proper it must also be such as to be readily joined thereto by welding or soldering. Heretofore it has been customary to utilize as a fusible section some alloy, such as that commonly known as "Magno" which comprises approximately 95 per cent manganese and 5 per cent of nickel. Such alloys, however, have been found objectionable, particularly for manufacturing purposes since they oxidize quite readily necessitating thorough cleaning before being joined to the leading-in conductor, otherwise a

good soldered connection cannot be made. Also, these alloys are exceptionally resilient which increases the difficulty of joining to the leading-in conductor since they tend to spring away from the leading-in conductor to which it is desired to connect the fusible section.

It is, accordingly, an object of my present invention to provide a fusible section for an electrical conductor which possesses the requisite current carrying characteristics and which may be readily joined to the remainder of the conductor proper.

Another object of my present invention is the provision of a fusible section particularly adaptable as a fuse for incandescent electric lamps 15 and the like wherein the fusible section may be readily joined to the filament support and leading-in conductor during the process of manufacture.

A further object of my present invention is the provision of a fusible section for a leading-in conductor for incandescent electric lamps formed of a material which does not readily oxidize and which is readily cleaned by flux or the like thus facilitating joining to the leading-in conductor proper by soldering.

Still further objects of my present invention will become apparent to those skilled in the art by reference to the accompanying drawing where-

Fig. 1 is an elevational view partly in section of an incandescent lamp constructed in accordance with my present invention showing the fused section disposed interiorly of the envelope, and

Fig. 2 is a view similar to Fig. 1 but illustrates the fuse section disposed exteriorly of the envelope.

Referring now to the drawing in detail I have shown in Fig. 1 an incandescent lamp of the usual construction which comprises an evacuated envelope 5 having the customary screw base 6 cemented or otherwise attached thereto. The envelope is provided with a reentrant press 7 and extending upwardly from this press is a supporting rod 8 to the extremity of which is secured a plurality of suitable wires 9 for resiliently supporting a filament 10 so as to allow for contraction and expansion of the latter when heated to incandescence by the passage of an electrical current therethrough.

Connected to the ends of the filament are a pair of leading-in conductors one of which 12 extends through the press 7 and is connected to the center contact point of the base 6. The other leading-in conductor 13 is likewise connected to

30

35

55

the opposite end of the filament and extends through the press 7 where it is connected to the shell of the base 6. In order to prevent the heat from the filament affecting the seal at the point where the leading-in conductors 12 and 13 pass through the press 7, particularly in high wattage lamps, an insulated baffle or the like 14 is provided which is supported by small lugs attached to the leading-in conductors. The leading-in conductor 13 has a fusible section formed integral therewith which comprises a short length of wire or ribbon 15 formed of an alloy as herein-after more fully described, which may be soldered to the remainder of the leading-in conductor. For the purpose of preventing hot metal from falling in the vicinity of the seal upon disruption of the fuse 15 it is surrounded by a sleeve of insulating material 16.

The construction thus far described constitutes essentially an incandescent lamp provided with what is termed an inner fuse which has long been known to the art. However, in accordance with my present invention I make the fuse of an alloy such as what is known as "Lohm" comprising approximately 93 per cent copper and 7 per cent nickel, or "Monel" which comprises approximately 60 per cent nickel, 33 per cent copper and 6.5 per cent iron with traces of other metals. Owing to the relatively high percentage of copper in combination with the nickel an alloy is formed which has the requisite electrical current carrying characteristics so as to be fused upon the passage of abnormal current flow. Moreover, these alloys become oxidized to a very slight extent thus facilitating soldering to the remainder of the leading-in conductor, since any oxidation is easily cleaned by flux or the like, and inasmuch as these alloys are relatively soft they can be shaped and retained adjacent the surface which it is desired to contact thus making automatic machine manufacture of the leading-in wire together with the fusible section practical.

In Fig. 2 I have shown a lamp similar in all respects to that shown in Fig. 1 with the exception that it is of smaller wattage, being less than 300 watts, and accordingly, is provided with a standard size screw base 6 in lieu of what is known as the "mogul" base 6 as shown in Fig. 1. Also in this instance an outer fuse is employed in that the fuse section 15 is disposed exteriorly of the envelope between the screw base 6 and the reentrant press 7. It is frequently desirable in the higher wattage lamps, i. e., 300 watts and higher, to provide an outer fuse, as shown in Fig. 2, so that it will become disrupted thus pre-

venting the energy from passing interiorly of the lamp which, because of the high wattage energy supplied might otherwise have a tendency to sustain the arc rather than extinguish it.

It thus becomes obvious to those skilled in the art that I have provided a fusible section which can be readily employed as an integral part of a leading-in conductor for an incandescent electric lamp. Inasmuch as the alloy which I employ not only has the requisite electrical current carrying characteristics but oxidizes very slightly and is thus easily cleaned by flux, or the like, and is sufficiently pliable as to be shaped as desired, it can be readily joined to the leading-in conductor proper which is naturally of a metal having a different coefficient of expansion.

Although I have shown and described one specific embodiment of my present invention I do not desire to be limited thereto as various other modifications thereof may be made without departing from the spirit and scope of the appended claims.

What is claimed is:

1. A fuse adapted to disrupt upon the passage of abnormal flow of electric current therethrough consisting of a slightly oxidizable, readily cleanable alloy including copper and nickel with each metal being present in excess of 25% of the total percentage of said alloy to render said fuse readily solderable to metals or alloys of a composition differing from said fuse.

2. A fuse adapted to disrupt upon the passage of abnormal flow of electric current therethrough consisting of a readily cleanable, slightly oxidizable alloy including copper in the proportion of 33% to 93% and nickel in the proportion of 60% to 70%, respectively, of the total percentage of said alloy to render said fuse readily solderable to metals or alloys of a composition differing from said fuse.

3. A fuse adapted to disrupt upon the passage of abnormal flow of electric current therethrough consisting of a readily cleanable, slightly oxidizable alloy including approximately 60% nickel, 33% copper and 6.5% iron and readily solderable to metals or alloys of a composition differing from said fuse.

4. A fuse adapted to disrupt upon the passage of abnormal flow of electric current therethrough consisting of a readily cleanable, slightly oxidizable and pliable alloy including approximately 93% copper and 7% nickel readily solderable to metals or alloys of a composition differing from said fuse.
